Nonlinear Dual Integrating Ramp ADC T. J. Harrison

[57]

ABSTRACT

An analogue-to-digital converter of the dual slope integration type has an integrator portion and analogue input signal of one polarity and a reference signal of opposite polarity, the two signals being alternately connected to the integrator portion. The invention includes means for generating a variable reference signal, the magnitude of which is varied in dependence on the magnitude of the analogue input signal, for producing a predetermined non-linear relationship between the analogue input and the digital output of the converter.

ANALOGUE-TO-DIGITAL CONVERTERS

BACKGROUND OF THE INVENTION

This invention relates to analogue-to-digital converters of the dual-slope integration type. It has particular but not exclusive application where it is required to convert to digital form an analogue signal derived from a transducer which has a non-linear relationship between its input and its analogue output.

In analogue-to-digital converters of the dual-slope integration type, an input voltage V_i to be digitised is switched to the input of an integrator for a fixed period of time t_1 . If the integrator time constant is RC and the integrator output voltage V starts at zero, then after a time t_1 ,

$$V = \frac{V_i t_1}{RC}$$

At the end of time t_1 the integrator is disconnected from V_i and connected to a stable reference potential V_R of opposite polarity to V_i . The integrator output voltage now reduces linearly towards zero and reaches the original value (zero) after a time interval t_2 given by:

$$t_2 = \frac{V RC}{V_R}$$

$$\therefore t_2 = \frac{V_i t_1}{RC} \times \frac{RC}{V_R} = \frac{t_1 V_i}{V_R}$$

Since t_1 and V_R are both constant, $t_2 \propto V_i$.

A clock pulse generator provides a train of pulses of constant frequency. The number of clock pulses occurring during the time interval t_2 is counted to provide a digital output signal corresponding to the analogue input V_i . It should be noted that the analogue input/digital output characteristic is linear. Such converters are therefore suitable for use when a digital signal corresponding to an electrical quantity is required, as for example in digital voltmeters and current meters.

When a signal corresponding to a non-electrical quantity such as temperature or pressure is required, a transducer is employed to produce an electrical analogue of the quantity. Frequently the input/output characteristic of the transducer is non-linear. If the analogue output of the transducer is applied to a converter of the type outlined above, the overall input quantity/digital output characteristic will also be non-linear. For example a digital temperature indicator may comprise a thermocouple feeding a digital voltmeter. The temperature/e.m.f. characteristic of thermocouples are in general non-linear, hence the digital output will not be directly proportional to temperature.

SUMMARY OF THE INVENTION

It is an object of the present invention to provide an analogue-to-digital converter having an input/output characteristic capable of being adjusted in conformity with the non-linear input/output characteristic of an analogue signal source such as a transducer so as to produce a substantially linear overall characteristic relating transducer input and digital output.

According to the invention, there is provided an analogue-to-digital converter of the dual slope integration type in which an analogue input signal of one polarity

and a reference signal of opposite polarity are alternately connected to an integrator circuit, including reference signal generating means whereby the magnitude of the reference signal is varied in dependence on the magnitude of the analogue signal so as to produce a predetermined non-linear relationship between the analogue input and the digital output of the converter.

The reference signal generating means may comprise means for deriving a first signal from the analogue signal such that the ratio of the magnitude of the first signal to the magnitude of the analogue signal bears one of a plurality of fixed numerical values, the one value being selected in dependence on the magnitude of the analogue signal, and means for summing the first signal 10 with a second signal of constant magnitude to provide the said reference signal.

The means for deriving the first signal may comprise a potential dividing network including a plurality of resistors each in series with a respective one of a corresponding plurality of switches, each of the switches being adapted to connect its corresponding resistor to the network so as to modify the dividing ratio of the latter when the output from the network attains a predetermined level uniquely associated with the said switch. 20

25 Means may be provided for controlling the polarity of the reference signal in dependence upon the polarity of the analogue input signal.

BRIEF DESCRIPTION OF THE DRAWINGS

30 In order that the invention may be more clearly understood, an embodiment thereof will now be described by way of example, with reference to the attached drawings of which:

35 FIG. 1 is a block schematic diagram of a known form of analogue-to-digital converter,

FIG. 2 illustrates the variation of the integrator output potential in the arrangement of FIG. 1,

FIG. 3 is a block schematic diagram of an analogue to digital converter according to the invention, FIG. 4 40 is a more detailed schematic diagram of a reference signal generator used in the embodiment of FIG. 3,

FIG. 5 is a characteristic curve used to illustrate the mode of operation of the embodiment of FIG. 3.

45 DESCRIPTION OF THE PREFERRED EMBODIMENTS

The essential elements of a known form of digital voltmeter employing the dual slope integration method will first be described with reference to FIG. 1.

50 An input voltage V_i to be digitised is applied via an input terminal 1 to a first fixed contact of a changeover switch 2. The movable contact of the switch 2 is connected to an input terminal 3 of an integrator circuit shown within the broken rectangle 4 and comprising an operational amplifier 5, an input resistor 6 of value R connected between the terminal 3 and the input of the amplifier 5 and a feedback capacitor 7 of value C connected between the output and the input of the amplifier 5.

60 A constant reference potential of magnitude V_R greater than the maximum value of V_i is provided by a reference voltage source not shown in FIG. 1, and is connected via a switch 16 which will be further described hereinafter to a second fixed contact of the switch 2. The switch 2 is controlled by a bistable trigger circuit 8 as indicated by the broken line 9 so as to connect V_i to the integrator input terminal 3 when the bis-

table is in its first stable state, and to connect V_R to terminal 3 when the bistable is in its second stable state. It is to be understood that the switch 2 may preferably comprise a solid state switching circuit rather than the mechanical switch which has been shown in FIG. 1 for greater clarity.

A clock pulse generator 10 feeds a train of pulses of constant frequency f_c to the input of a recycling binary counter 11 arranged to produce an output pulse for every N clock pulses and immediately reset itself to zero count. The output of the counter 11 is connected to the trigger input of the bistable 8.

A binary store 12 has its individual stage inputs connected to the corresponding stages of the counter 11 so that it continuously records the count state of the latter. The outputs of the store 12 are connected to the inputs of a decode and display unit 13.

The output terminal 14 of the integrator 4 is connected to the input of a zero crossing detector circuit 15 which is adapted to produce a pulse at its output each time the signal applied to its input passes through zero. The output of the unit 15 is connected to a transfer input of the store 12, and also to a count reset input of counter 11 such that a pulse from detector 15 causes the current count state of counter 11, as recorded, in store 12 to be transferred to the decode and display unit 13 and also causes counter 11 to be reset to the zero count state.

The operation of the circuit of FIG. 1 will not be described with additional reference to FIG. 2, which shows the integrator output voltage with respect to time for a small (curve a) and a large (curve b) value of input voltage V_i .

Assume that at a time t_0 a cycle of the counter 11 is just commencing, i.e. the instantaneous value of the count is zero, and that the counter output pulse has reset the bistable 8 to its first stable state. The switch 2 is therefore set to connect the input voltage V_i to the integrator input terminal 3. As will become apparent, at time t_0 the instantaneous value of the integrator output voltage V is zero.

V then rises linearly, as shown by FIG. 2 at a rate determined by the magnitude of V_i , and continues to rise until after a time interval t_1 , counter 11 reaches its maximum count state and the resulting pulse sets the bistable 8 to its second stable state. This has the effect of disconnecting V_i from the integrator input terminal 3 and connecting V_R to terminal 3. The time interval t_1 is determined by the capacity N of the counter 11 and the frequency f_c of the clock pulse generator 10 in accordance with the relationship $t_1 = N/f_c$.

Since V_R is of opposite polarity to V_i , the output voltage V now commences to fall linearly at a rate determined by the magnitude of V_R , reaching its original value (zero) after a further time interval t_2 . As shown hereinbefore, $t_2 \propto V_i$.

When the integrator output voltage reaches zero, an output pulse is produced by the zero crossing detector 15 and is applied to the transfer input of the store 12. At the commencement of the time interval t_2 the instantaneous value of the count in the counter 11 is zero. During t_2 , clock pulses are counted and the count is registered in the store 12. The effect of the output pulse from unit 15 is to transfer the binary number n of clock pulses occurring during the interval t_2 to the decode and display unit 13. Since $t_2 = n/f_c$, n is proportional to V_i .

In unit 13, the binary number n is decoded into decimal notation and used to drive a numerical display giving a direct read-out of the magnitude of the input signal V_i .

A further effect of the pulse from the zero crossing detector 15 is to reset the counter 11 to zero. The counter therefore gives an output pulse which resets the bistable 8, reconnecting the input voltage V_i to the integrator input terminal, and a further measurement cycle begins, at the end of which the decode and display unit 13 is updated.

In FIG. 2, the integrator output voltage V is shown as increasing from zero to a positive value during the interval t_1 and falling again to zero during t_2 . Since the output of the integrator 4 is inverted with respect to its input, this requires that V_i is of negative polarity and V_R is of positive polarity. It is apparent that if V_i were positive and V_R negative, V would fall from zero to a negative value during t_1 and rise again to zero during t_2 , the operation of the circuit being otherwise as hereinbefore described.

In order that the integrator may respond to input signals of either polarity there may be provided two reference voltages V_R and $-V_R$ of equal magnitude and opposite polarity connected respectively to first and second fixed contacts of changeover switch 16 whose movable contact is connected to the second fixed contact of the switch 2. Preferably the switch 16 comprises a solid state switching circuit rather than the mechanical which is the switch shown in FIG. 1 for the purposes of clarity. Switch 16 is controlled, as indicated by the broken line 17, by the output of a polarity detection circuit 18 whose input is connected to the output terminal 14 of the integrator 4. If the integrator output potential goes positive during t_1 , the polarity detector 18 provides an output signal which causes the switch 16 to select the negative reference potential $-V_R$. Conversely if V goes negative then $+V_R$ is selected. The polarity detector 18 may also drive a visual display (not shown) to indicate the polarity of the input signal V_i .

In the analogue-to-digital converter described with reference to FIG. 1, the value of the numerical output displayed by unit 13 is linearly related to the magnitude of the input signal V_i .

There will now be described an arrangement according to the present invention, with reference to FIGS. 3 and 4. Circuit elements whose nature and function have already been described have been given identical reference to those employed in FIG. 1 and are not further described hereinbelow.

Referring to FIG. 3, the analogue input terminal 1 is connected to the input terminal 3 of the integrator 4 via a switch 19 and is further connected to an input of a reference signal generator unit shown generally by the broken rectangle 20. Unit 20 will be more particularly described hereinafter with reference to FIG. 4. A signal of constant positive potential $+V_C$ is also supplied to unit 20 from a stable source not shown in FIGS. 3 and 4.

The output of unit 20 is connected to the input of an inverting amplifier 21 having a gain of -1 , and also to the second fixed contact of the switch 16. The output of the amplifier 21 is connected to the first fixed contact of the switch 16 whose movable contact is connected, via a switch 22 to an input terminal 23 of the integrator 4. Within the integrator 4, the terminal 23 is

connected to the input of the amplifier 5 by way of an input resistor 24.

The switches 19 and 22 are both controlled by the bistable circuit 8 in such a way that when the switch 19 is closed the switch 22 is open and vice versa. Preferably solid state switching devices are employed for the switches 19 and 22.

Referring now to FIG. 4, in the reference signal generator unit 20, the analogue input signal is connected to one end of a resistor 25 whose other end is connected to a connection line 26. Resistors 27 and 28 each have one end connected to the line 26, and their other ends connected to the emitter electrodes of respective P.N.P. transistors 29 and 30. The base electrode of the transistor 29 is connected to a line 31 carrying a constant potential $+V_1$ from a stabilised source not shown in the drawing. The base of the transistor 30 is similarly connected to a line 32 carrying a constant potential $+V_2$. The collector electrodes of the transistors 29 and 30 are connected together and to a line 33 carrying zero potential.

The line 26 is connected to an input of an operational amplifier 34 via an input resistor 35. The constant potential $+V_c$ is connected to the said input via an input resistor 36. A feedback resistor 37 is connected between the output and the input of the amplifier 34.

In the arrangement shown, for all negative values of V_i , the transistors 29 and 30 are cut off and no current flows in the resistors 27 and 28. If the resistors 36 and 37 are equal in value the output voltage V_{REF} produced by the amplifier 34 is equal to the algebraic sum of V_c and $(V_i \times k)$ where k is the resistance ratio of the sum of the resistors 25 and 35 to the resistor 37. The same holds true for small positive values of V_i such that the potential on the line 26 is less than $+V_1$. For greater positive values of V_i , the transistor 29 conducts. The resistors 25 and 27 now form a potential divider for the analogue input V_i . The effect is to reduce the value of k . For still higher positive values of V_i the transistor 30 also conducts, connecting the resistor 28 in parallel with the resistor 27 and thereby further reducing the value of k .

The operation of the arrangement described with reference to FIGS. 3 and 4 will now be described.

Assume that in the integrator 4 the resistor 24 is equal in value to the resistor 6. The arrangement comprising the switches 19 and 22 and the resistors 6 and 24 shown in FIG. 3 is then electrically equivalent to that shown in FIG. 1 and comprising the switch 2 and the resistor 6.

The analogue input V_i is connected to the input of the integrator 4 for a time interval t_1 determined by the counter 11 precisely as hereinbefore described with reference to FIG. 1. During the time interval t_1 the polarity detector 18 sets the switch 16 to select either the output $-V_{REF}$ from the reference signal generator 20 or the output $+V_{REF}$ from the inverting amplifier 21 accordingly as the potential V at the output of the integrator has positive or negative polarity. At the end of the time interval t_1 the switches 19 and 22 are reversed, so disconnecting the input voltage V_i from, and connecting the selected reference potential to, the integrator input. The integrator output then runs back towards zero for a time interval t_2 which is terminated by an output pulse from the zero crossing detector 15.

The manner in which the time interval t_2 varies with the value and polarity of the input voltage V_i will be de-

scribed with reference to FIG. 5, in which values of V_i are plotted as abscissae and those of t_2 as ordinates.

Assume initially that k is very small. The contribution of V_i to the reference signal V_{REF} will then be negligible, and t_2 will vary substantially linearly with V_i as shown for negative inputs by the chain dotted line 38a, and for positive inputs by the line 38b.

Now assume that, for values of V_i such that the transistors 29 and 30 are cut off, the value of k is unity, i.e. 10 that the sum of the values of the resistors 25 and 35 are equal to the value of the resistor 36 (and that of the resistor 37). For small values of V_i , its contribution to the reference voltage V_{REF} is likewise small and V_{REF} is substantially equal to $\mp V_c$ according as V_i is negative 15 or positive. As V_i becomes increasingly more negative, the value of V_{REF} progressively decreases, until a point is reached at which V_i has equal magnitude with V_c but is of opposite polarity when V_{REF} equals zero. For this condition the integrator output voltage V remains constant during t_2 , and t_2 therefore becomes infinite. For negative inputs the relationship between V_i and t_2 follows a curve such as 39, tangential to curve 38a at $V_i = 0$ and approaching asymptotically the broken line 40 corresponding to $V_i = -V_c$.

For increasing positive values of V_i the value of V_{REF} is progressively increased. Hence t_2 becomes progressively less, by comparison with the $k=0$ case. In the absence of the transistors 29 and 30 and the corresponding resistors 27 and 28, the value of k would remain 30 unity for all positive values of V_i , and the relationship between t_2 and V_i would follow a smooth curve such as 41. In practice however, when V_i reaches a value indicated in FIG. 5 by the broken line 42, the transistor 29 commences to conduct, thereby reducing the value of 35 k , so that for higher values of V_i the relationship follows a curve such as 43 up to a point indicated by the line 44 where the transistor 30 also conducts. This further reduces the value of k , and thereafter the relationship follows a curve such as 45.

It will be apparent that if the initial value of k is less than unity, then the curve 39 will approach infinity for a value of V_i correspondingly more negative than $-V_c$, i.e. it will approach more closely to the linear relationship shown by the curve 38a. Similarly, for positive values of V_i the combined curve 41-43-45 will approach more closely the curve 38b. If k is initially greater than unity, the departures from linearity will be correspondingly greater than those shown in FIG. 5.

In the reference signal generator 20 there may be 50 provided further series combinations each comprising a transistor and a resistor connected between the junction 26 and the zero potential line 33, each of the additional transistors being arranged to conduct when the potential on the junction 26 reaches a predetermined level so as to provide additional points at which the value of k is modified. One or more of such additional transistors may be arranged to conduct when the potential on the line 26 exceeds a predetermined negative potential. Furthermore, the constant input V_c may be 55 arranged to have a negative instead of a positive potential. In this last case, the operation will be as described with reference to FIGS. 4 and 5 but with reversed polarities of the input signals.

Thus, in an analogue to digital converter according 60 to the present invention the relationship between this analogue input signal and the digital output corresponding to the time interval t_2 may be adjusted so as

to approach a desired non-linear characteristic within close limits. In particular it may be made to approach the characteristic necessary to provide compensation for the non-linear input/output characteristic of a transducer whose output is to be digitised so that the digital output signal is substantially directly proportional to the input to the transducer. The transducer may be a thermocouple and the equipment may provide a digital read-out of temperature.

In the known arrangement described with reference to FIG. 1, the reference signal supplied to the integrator input is always of greater magnitude than the analogue signal, and consequently the time interval t_2 is always less than the time interval t_1 . Hence the number of clock pulses occurring during t_2 is always less than the capacity of the counter 11.

In arrangements according to the present invention there is a range of values of V_i for which the magnitude of the reference signal V_{REF} is less than that of V_i . In the absence of suitable provision, this would result in the time interval t_2 being greater than t_1 and consequently in the counter 11 being overfilled.

For this reason the reference signal V_{REF} is supplied via the switch 22 to the integrator input terminal 23, whence it is fed to the input of the amplifier 5 via the input resistor 24, while the analogue signal V_i is fed via terminal 3 and input resistor 6. The integration time constant is CR for the analogue signal and CR_1 for the reference signal where C , R and R_1 represent the values of the capacitor 7 and the resistors 6 and 24 respectively. By making R_1 less than R , it can be arranged that for all values of V_i within the working range the integrator output voltage returns to zero in a time interval t_2 less than t_1 .

What we claim is:

1. In an analogue-to-digital converter of the dual slope integration type having an integrator portion, an analog input signal of one polarity, a reference signal of opposite polarity being supplied thereto and including means for alternately connecting said input signal

40

45

50

and reference signal to said integrator portion, said improvement comprising:

means for generating a variable reference signal, the magnitude of said variable reference signal being varied in dependence on the magnitude of the analogue input signal, for producing a predetermined non-linear relationship between the analogue and the digital output of the converter.

2. An analogue-to-digital converter according to claim 1 in which said means includes a first means for deriving a first signal from the analogue signal such that the ratio of the magnitude of the first signal to the magnitude of the analogue signal bears one of a plurality of fixed numerical values, one of said values being selected in dependence on the magnitude of the analogue signal, further including a second means which supplies a constant reference signal and a summation unit for summing the first signal with the constant reference signal to provide the said variable reference signal.

3. An analogue-to-digital converter according to claim 2 wherein the means for deriving the said first signal comprises a potential dividing network including a plurality of resistors each in series with a respective one of a corresponding plurality of switches, each of the switches being adapted to connect its corresponding resistor to the network so as to modify the dividing ratio of the latter when the output from the network attains a predetermined level uniquely associated with the said switch.

4. An analogue-to-digital converter according to claim 3 wherein each switch comprises a transistor and wherein the said predetermined level is determined by an appropriate bias voltage applied to the base of the transistor.

5. An analogue-to-digital converter according to claim 1 including means for controlling the polarity of the reference signal in dependence upon the polarity of the analogue input signal.
